[57] CLAIM

The ornamental design for a visor phone number index, as shown and described.

DESCRIPTION

FIG. 1 is a perspective view showing my new design;

FIG. 2 is a front view thereof;

FIG. 3 is a rear view thereof;

FIG. 4 is a right side view of the design;

FIG. 5 is a left side view of the design;

FIG. 6 is a top view of the design;

FIG. 7 is a bottom view of the design;

FIG. 8 is a front view of the design shown in its open position; and,

FIG. 9 is a rear view of the design shown in its open position.

The broken line representation of the outline of an automobile visor in FIG. 1 is for the purpose of illustration only, and forms no part of the claimed design.
